GUIBERSON CORPORATION, OF DALLAS, TEXAS, A CORPORATION OF DELAWARE.

UNDERREAMER.

1,368,961.

Specification of Letters Patent. Patented Feb. 15, 1921.

Application filed June 7, 1920. Serial No. 387,129.

To all whom it may concern:

Be it known that I, GUSTAVUS A. MONTGOMERY, citizen of the Republic of Finland, residing at Dallas, in the county of Dallas 5 and State of Texas, have invented certain new and useful Improvements in Underreamers, of which the following is a specification.

This invention relates to new and useful 10 improvements in underreamers.

An important result sought by the invention is the provision of greater bearing areas for the bits, whereby more amplified surfaces are offered in sustaining the end 15 thrusts, than is usually present in the reamers now in use. A further aim of the invention is to strengthen the bit at the intersection of the bit-body and the shank, thus eliminating a weak point, where fracture often occurs. The invention also 20 involves longitudinal and radial bearing surfaces of an extensive nature, whereby the bits are braced against transverse, lateral and longitudinal strains and are more substantially supported. Another important 25 point involved in the invention is a spring actuated expanding mechanism for the bits which includes a centrally located expanding element co-acting with the bits and the 30 reamer body in such a manner as to produce a more efficient and satisfactory operation.

In carrying out the invention a reamer body is provided at its lower extremity with a tongue which constitutes an expanding 35 element. A pair of bits are mounted substantially on each side of the tongue so as to swing in planes parallel to the tongue, and are provided with channels receiving the tongue; whereby guides are had for the 40 bits while the same are being expanded; and also whereby a brace is provided which prevents the bits from collapsing during the reaming operation and further braces them against torsional and lateral strains.

The bits are pivotally supported and are 45 connected by a transverse member. Resilient means for retracting and thus expanding the bits, is connected with the bits through their pivotal support. The tongue 50 co-acts with the resilient means in expanding the bits and this is one of the important features of the invention. The body is pro-

vided with diametrically opposite recesses or sockets in its outer sides for receiving shanks formed integral with the bits, the 55 transverse member referred to engaging said shanks. It is preferable to taper the sockets and the shanks so as to fit therein so that said shanks will wedge in the sockets when the bits are expanded, thus taking the 60 strain off of the resilient retracting means until the bits are displaced from the sockets.

In fact it has been found advantageous to make the contacting surfaces at a number of 65 points in the reamer, tapering, whereby repairing is facilitated by cutting back the transverse surfaces so that play between the tapering surfaces is thus taken up. The readiness with which a reamer may be repaired without rebuilding the same adds 70 considerable to its value.

A very important feature in a preferred form of the invention is found in tapered splines disposed longitudinally of the body 75 for receiving each bit. These splines amplify the bearing surfaces so as to take lateral and tangential strains as well as end 80 thrusts. Another point in favor of the spline is that when the shanks become loose in the sockets the bits may be removed, heated and driven on the splines, thus taking up play and temporarily restoring the reamer to good condition.

Another point of novelty resides in tapering the expanding tongue and channels of 85 the bits to correspond therewith so that when said bits are expanded they will have a tendency to wedge onto the tongue, however this is not an essential feature. It has been found advantageous to include a spring 90 pressed runner which is radially projected from the body to travel on the inside of the casing and to operate a latch normally holding the bits contracted and the spring actuating means in restraint; but arranged to 95 withdraw the latch to release the spring actuating means when the reamer has been lowered below the casing, whereby the bits are expanded.

In order to prevent loss of the bits, in case 100 all of the sustaining elements which support the bits should be broken, safety projections are provided on the tongue so as to be received in recesses in the bits when the lat-

ter are released and drop down. These projections are located so as to arrest the bits before the dove tails can disengage from their grooves, thereby preventing lateral displacement of the parts. This is a very important feature.

I prefer to employ a central mandrel within the body and provide the same with a cross head which engages in counter bores in the bits; together with a retracting spring surrounding the mandrel and means for holding the bits in pivotal relation to the mandrel, but the invention is not to be confined to this particular construction.

5 A very important structural feature is the strengthening of the intersection of the shank and bit and this is accomplished by building up the bit above its shoulder; thus increasing the material at this point and reducing the liability of breakage.

The invention will be more readily understood from a reading of the following specification and by reference to the accompanying drawings, in which an example of the invention is shown, and wherein:

Figure 1 is a view of a reamer constructed in accordance with my invention, a portion of the reamer being in section and a portion in elevation and the bits being expanded,

0 Fig. 2 is a similar view showing the bits contracted,

Fig. 3 is a view at right angles to Fig. 1, the major portion being in section and the lower portion being in elevation,

5 Fig. 4 is an elevation of the reamer-body, the upper portion being in section,

Fig. 5 is a longitudinal sectional view of the reamer body,

Fig. 6 is a cross-sectional view on the line 6—6 of Fig. 5,

Fig. 7 is an under side view of the reamer with the bits contracted,

Fig. 8 is a similar view with the bits expanded,

45 Fig. 9 is a cross-sectional view on the line 9—9 of Fig. 4,

Fig. 10 is a cross-sectional view on the line 10—10 of Fig. 5,

50 Figs. 11 to 14 inclusive are details of one of the bits showing all four sides of the same,

Fig. 15 is a plan view of one of the bits,

Fig. 16 is a detail of the pivot bolt,

Fig. 17 is a detail of the mandrel.

55 Fig. 18 is another view of the mandrel at right angles to Fig. 17, and

Fig. 19 is an elevation of the wedge tool used in collapsing the bits.

In the drawings the numeral 10 designates an elongated reamer body having a tapered screw-threaded socket 11 at its upper end for receiving the lower end of the coupling member (not shown) by which the reamer is connected with its operating means. The body has flattened portions 12 on opposite

sides, whereby a wrench grip is provided for 65 turning the body in connecting and disconnecting it from its coupling.

An expanding element in the form of a tongue 13 is formed integral with the body at its lower end. The tongue is located centrally of the body. On each side of the tongue and parallel thereto are vertical grooves 14, which latter are angular in cross-section and flare downwardly and outwardly with relation to the sides of the tongue as is 75 best shown in Fig. 5. It is desirable, but not essential, to taper or reduce the tongue in a downward direction whereby it is given a wedge shape. Radial recesses 15 extend outwardly from the grooves to the outer 80 surface of the body and in conjunction with said grooves, form dove-tail sockets as is clearly shown in Fig. 6, 9 and 10.

It will be noted that the tongue extends below the body proper and particularly, has 85 its vertical edges perpendicular. The tongue is less in width than the diameter of the body and is comparatively thin. The body is cut back from its lower end to form a shoulder 16 at one side of its recess 15 on each side of 90 the tongue, thus removing the metal to the plane of, and co-incident with the flat side of the tongue. On the side of the tongue, a spline 17 extends downwardly on each side of the body. The inner edge of each spline 95 is contiguous to the adjacent groove 14 and is tapered in harmony therewith. The outer edge of each spline is also tapered accordingly. It will be noted that the grooves 14 flare downwardly in two directions, the radial projection of the splines conforming to 100 one flare and the vertical edges conforming to the other flare.

A pair of bits 18 are each provided with an offset shank 19 extending vertically. This 105 provides each bit with a shoulder 20 extending laterally with relation to the inner face of the shank as is best shown in Figs. 11 and 13. In order to strengthen the bits each is built up laterally to one side of its shank by 110 forming a boss 21 in the angle at the intersection of the bit body or cutter portion and thus producing an elevated shoulder 22 on top of the boss. Each bit has its outer surface rounded and is provided at its lower end with an arcuate cutter 23 projecting outwardly. The under surface of each cutter is beveled inwardly and upwardly. This 115 gives two bevels to the cutters, thus permitting the same to be readily sharpened.

The bit body is cut away under each shank and formed with a web 24 having one side face in a vertical plane contiguous to the inner faces of the boss 21 and the shank 19 thereof. The inner edge of each web is inclined upwardly to the center of the bit. This leaves each bit with a laterally projecting wing 25 as is well shown in Figs. 11, 13

and 15. It will be seen that in each bit the shank 19 and bit body which includes the wing 25, are tied together by the boss 21 and the web 24, and these parts brace the bits in the line of radial strain incidental to their expansion and operation; thereby preventing breakage at this point.

Each shank is tapered upwardly on each side and its inner face is also tapered or inclined upwardly. The shanks are shaped to fit the socket formed by the grooves 14 and recesses 15, thus each exhibits a dove-tail shape in plan. This causes each shank to have vertical ribs 26 along each side, flush with the inner face and engaging in the grooves 14.

The tongue 13 has a central longitudinal slot 27 extending upwardly from opposite the lower end of the body 10 to the tops of the dove-tail sockets, where it meets a central counter bore 28 which merges at its upper end into a main bore 29. At the intersection of the bores 28 and 29 an annular shoulder 30 is formed. The main bore terminates at the socket 11. A central mandrel 31 disposed in the main bore extends down through the counter bore 28 and into the slot 27. At its lower end the mandrel carries a tubular cross-head 32 projecting on each side of the tongue 13 from the slot. Transverse openings 33 are provided through the upper ends of the shanks and each opening has a countersunk seat 34 in the inner face of the shank. The seats receive the ends of the crosshead, whereby the bits are pivotally supported by the crosshead and the mandrel.

For taking up the play between the parts a cross bolt 35 is passed through the openings 33 and the crosshead. Each shank has on its outer face a vertical key seat 36 bisecting an annular recess 37 surrounding the outer end of the opening 33. As is shown in Figs. 3 and 16 the bolt 35 has its screw threaded end engaging in an annular nut 38 which is seated in one of the recesses 37 and is formed with a peripheral lug 39 projecting into the seat 36, whereby the nut is countersunk below the outer surface of the shank and is held against rotation. The bolt has a head 40 on its opposite end engaging in the recess 37 of the other shank. The bolt head has an angular wrench socket 41 at its center intersected by diametrical apertures 42. A wrench (not shown) is inserted in the socket 41 and the bolt screwed into the nut. When the parts are tight a cotter pin 43 is passed through the apertures from the recess 36, whereby the bolt is fastened against rotation.

A washer 44 surrounding the mandrel rests on the shoulder 30 and supports the lower end of a coiled spring 45 encircling the mandrel within the main bore. A cap

46 is screw threaded on the upper end of the mandrel and confines a washer 46' on top of the spring. An expansion spring is employed and tends to force the mandrel upwardly, thereby drawing the shanks into the sockets.

Referring again to the bits it will be noted that the inner faces of the same engage the sides of the tongue 13. Each wing 25 has an upwardly flaring channel 47 conforming to the taper of the sides of the tongue, the bottom of the channel being perpendicular like the edges of the tongue. In the inner face of each boss 21 a sump 48 is provided. The sumps are shaped and proportioned to snugly receive the splines 17, which may be wedged into said sumps. The channels receive the vertical edges of the tongue and act as guides.

When the bits are lowered the sumps are carried below the splines thus permitting the bits to swing inwardly and collapsed as is shown in Fig. 2. The lower end of the tongue is curved and the upper ends of the channels are rounded at 47'; thus when the bits are collapsed the rounded ends 47' ride under the under corners of the rounded end of the tongue. The rounded ends 47' thus assist the shoulders 20 in riding under the tongue, whereby the tongue takes the upward thrust of the spring 45. To permit the bits to be lowered and collapsed, it is necessary for the shanks to swing and therefore one corner of the upper end of each shank is cut off at 49 and a notch 50 is cut in the other side of the shank near its center. The sockets of the head have beveled portions 49' receiving the ends 49 when the shanks are drawn into the sockets.

When the bits are lowered and the rounded ends 47' ride under the tongue; the beveled ends 49 permit the shanks to swing, the notches 50 receiving the lower corner of the reamer body, as is shown in Fig. 2. The bits have their outer surfaces shaped so as to ride true down the casing, when collapsed. When the bits are collapsed the cutters 23 are well within the diameter of the reamer and thus cannot strike or catch in the joints. In order to collapse the bits it is necessary to force the mandrel downward against the tension of the spring 45 and for this purpose a wedge 51 (Fig. 19) is inserted through slots 52 in the body 10 so that its lower edge bears on the top of the cap 46. By driving the wedge transversely through the body 10 the mandrel is forced downward and the bits carried downward until their shoulders 20 can be swung inward under the tongue. The wedge is left in place until the bits are inserted in the casing.

While the rounded outer surfaces of the bits would ride on the inner surface of the

easing and hold themselves collapsed, I prefer to use other means. In the side of the reamer body I provide a vertical cavity 53 in which a radial runner 54 is mounted. 5 The runner has coiled springs 55 projecting from its rear edge, bearing against the back wall of the cavity and tending to force the runner outwardly. The runner has a depending pin 56 engaging in the slotted shank of a spring pressed latch 57 extending inward in the body 10. The mandrel has an annular shoulder 58 which is engaged under the latch when the mandrel is depressed to collapse the bits. So long as the 10 runner is in the casing it cannot move outward sufficiently for its pin to withdraw the latch. However just as soon as the runner rides below the casing the runner is freed, so that its springs 55 will force it outward far enough to withdraw the latch 57 and release the mandrel.

When the reamer is lowered in the well and the bits carried below the shoe at the bottom of the casing so as to be released, 25 the mandrel 31 is free to be impelled upward by its compressed spring 45. The tension exerted on the mandrel causes the shoulders 20 to ride outwardly and upwardly over the curved end of the tongue 13. The 30 lower corners of the tongue are given a greater curvature, so that the shoulders 20 will more readily ride off the same. As the shoulders 20 ride off the rounded corners of the tongue, the channels 47 are entered by 35 the perpendicular edges of the tongue, whereby the bits are guided as they are expanded. The mandrel through its cross head 32 pulls the shanks 19 into the dovetail sockets, the ribs 26 sliding in the 40 grooves 14 and the splines 17 entering the sumps 48.

It is pointed out that the tapering surfaces of the channels will engage the tapering sides of the tongue; while the tapering 45 shanks will engage the tapering sockets and the splines wedge in the sumps. This contact of inclined and tapering surfaces will cause the parts to wedge together, whereby a tight fit will be had and by leaving a clearance between transverse contacting surfaces, wear is taken up by the parts wedging together. Should the parts become badly 50 worn the bits may be removed, heated and then driven on the splines and the play 55 taken up by tightening the bolt 35.

As the bits come to rest in the sockets the shoulders 22 engage the shoulders 16 of the reamer body and the shoulders 20 engage the lower end of the reamer body. It will 50 be seen that the shoulders 20 and 22 and the top of the shanks 19 give transverse bearing areas of a large amplitude and considerably more than is present in other reamers now in general use; and thus end 55 thrusts are not only sustained by the wedg-

ing surfaces but by the transverse surfaces which make an extremely strong and durable reamer.

Attention is called to the tongue 13 disposed between the expanded bits and engaging in the channels 47. By this arrangement the bits are braced against collapsing inwardly when in operation as well as against lateral and torsional strains. Each bit is also braced against radial strains by 75 the dove-tail shape of the shanks and the splines 17 and against transverse strains by 75 bosses 21 and the tongue 13. It will be seen that the bits are virtually supported against strains in all directions and will undergo 80 extremely heavy duty without breaking down.

It is pointed out that the cross-head 32 gives a large bearing surface for the seats 85 34 of the shanks and the weight of the shanks is carried on the head and not on the bolt 35; a very strong and durable construction. It will be seen that should the bolt be broken the shanks cannot be disengaged from the mandrel until the bits fall 90 far enough to disengage the ribs 26 from the grooves 14. To prevent this disengagement however and to provide a safety feature so that a bit cannot be lost in the well 95 unless broken through the boss 21 or lower down, I provide a recess 59 in the inner face for engaging a lug 60 on each side of the tongue.

This application is a continuation in part of my application filed October 23rd, 1919, 100 Serial Number 332,641, and allowed December 31st, 1919.

What I claim is:

1. In an underreamer, a reamer body, an integral central tongue depending at the lower end of the body, said body having vertical sockets at its lower end on each side of the tongue, bits disposed at the vertical edges of the tongue and having portions overlapping the sides of the tongue, shanks 105 extending upwardly from the bits on the sides of the tongue and engaging in the sockets, and spring impelled means mounted in the body for pivotally supporting said bits, said means being connected with the shanks and acting to draw the shanks into the 110 sockets for expanding the bits.

2. In an underreamer, a reamer body, an integral central tongue depending at the lower end of the body, said body having vertical sockets on each side of the tongue and said sockets having enlargements at the sides of the tongue, bits disposed at the vertical edges of the tongue and having portions overlapping the sides of the tongue, shanks 120 extending upwardly from the bits on the sides of the tongue and engaging in the sockets, vertical projections on the shanks 125 engaging in the enlargements of the sockets for holding said shanks against out- 130

ward displacement, said shanks sliding vertically in the sockets, and spring actuated means located in the reamer body and pivotally supporting the shanks for expanding 5 the bits.

3. In an underreamer, a reamer body, an integral central tongue depending at the lower end of the body, said body having vertical sockets on each side of the tongue 10 and said sockets having enlargements at the sides of the tongue, bits disposed at the vertical edges of the tongue and having portions overlapping the sides of the tongue, shanks extending upwardly from the bits 15 on the sides of the tongue and engaging in the sockets, vertical projections on the shanks engaging in the enlargements of the sockets for holding said shanks against outward displacement, said shanks sliding vertically in the sockets, spring actuated means 20 located in the reamer body and pivotally supporting the shanks for expanding the bits, and means co-acting between the tongue and the bits for limiting the downward displacement of the shanks to prevent 25 their disengagement from the sockets.

4. In an underreamer, a reamer body, an integral central tongue depending at the lower end of the body, said body having 30 radial dove-tail sockets extending vertically on each side of the tongue, and spring sustained bits having dove-tail shanks fitting vertically in said sockets, said bits having vertical channels receiving the vertical 35 edges of the tongue, said tongue being disposed between said bits.

5. In an underreamer, a reamer body, a longitudinally projecting relatively thin wedge-shaped tongue located centrally at 40 the lower end of the body and having opposed sides converging downwardly, and bits pivotally and resiliently connected with the body having vertical wedge-shaped channels conforming to the taper of the 45 tongue, said channels receiving the edges of the bits which wedge on said tongue when expanded.

6. In an underreamer, a reamer body, an integral central tongue depending at the 50 lower end of the body, said body having vertical sockets at each side of the tongue and being stepped at its lower end, a pair of bits having stepped shoulders co-acting with the stepped lower end of the body, 55 said bits having vertical channels receiving the edges of the tongue, shanks slidably and pivotally engaging in said sockets of the body, and spring actuated contracting means located in the body and pivotally 60 connected with the shanks.

7. In an underreamer, a reamer body, a tongue at the lower end of the body, said body having vertical sockets at its lower end, a pair of bits having channels for receiving 65 the tongue and swinging under the

tongue when lowered, shanks extending upwardly and slidably in the sockets, spring actuated means for drawing the bits upwardly, whereby they are expanded by the tongue which is received in the channels, 70 said spring means being pivotally connected with the shanks, and a spring actuated latch device carried in the reamer body for holding the spring retracting means in restraint, whereby the bits may be collapsed under the 75 tongue.

8. In an underreamer, the combination of a reamer body, an integral tongue depending at the lower end of the body, said tongue having a vertical slot, said body having vertical sockets on each side of the tongue, downwardly extending splines on each side of the tongue, a pair of bits having vertical channels receiving the edges of the tongue and provided with sumps receiving 80 the splines, shanks extending upwardly from the bits and slidably engaging in the sockets, a mandrel disposed within the reamer body and having its lower end in the slot of the tongue and pivotally engaging 85 the shanks, and a coiled spring connected with the mandrel for impelling the latter upwardly in the reamer body to draw the shanks into the sockets and the sumps about the splines, the bits being movable downwardly against the tension of the spring and collapsible under the tongue, the bits being withdrawn from the splines when collapsed. 90

9. In an underreamer, the combination of a reamer-body, an integral tongue depending from the lower end of the body and having a vertical slot, vertical sockets tapered upwardly in the body on each side of the slot of the tongue, a pair of bits having shoulders engaging under the tongue when 100 said bits are collapsed, said bits having vertical channels receiving the vertical edges of the tongue when said bits are expanded, tapering shanks extending upwardly from the bits and engaging in the sockets of the body, 105 a mandrel having pivotal connection at its lower end with the shanks through the slot of the tongue, and a coiled spring engaging the mandrel for impelling the same upwardly to draw the shanks into the sockets, 110 whereby the tongue expands the bits. 115

10. In an underreamer, the combination of a reamer-body, an integral tongue depending from the lower end of the body and having a vertical slot, vertical sockets tapered upwardly in the body on each side of the slot of the tongue, a pair of bits having shoulders engaging under the tongue when 120 said bits are collapsed, said bits having vertical channels receiving the vertical edges of the tongue when said bits are expanded, tapering shanks extending upwardly from the bits and engaging in the sockets of the body, a mandrel having pivotal connection at its lower end with the shanks through the slot 125 130

of the tongue, a coiled spring engaging the mandrel for impelling the same upwardly to draw the shanks into the sockets, whereby the tongue expands the bits, a spring pressed 5 latch engaging the mandrel for holding the same in a downward position when the bits are collapsed, and means in the body for automatically withdrawing the latch and releasing the mandrel when carried below the 10 well casing shoe.

11. In an underreamer, a reamer body, a tongue depending centrally from the lower end of the body and having a vertical slot, a pair of bits mounted on each side of the 15 tongue and having shoulders engaging under the tongue when collapsed, the body having tapering sockets extending vertically on each side of the slot, tapering shanks extending upwardly and slidably engaging 20 in the sockets, said shanks having side recesses, a mandrel slideable in the reamer body, a cross-head on the mandrel extending through the slot of the tongue and pivotally mounted in the side recesses for supporting the shanks, means for confining the 25 shanks on the cross-head, and a coiled spring in the reamer body exerting an upward tension on the mandrel.

12. In an underreamer, a reamer body, 30 a tongue depending centrally from the lower end of the body and having a vertical slot, a pair of bits mounted on each side of the tongue and having shoulders engaging under the tongue when collapsed, the body 35 having tapering sockets extending vertically on each side of the slot, tapering shanks extending upwardly and slidably engaging in the sockets, a mandrel slideable in the reamer body, a cross-head on the mandrel 40 extending through the slot of the tongue and pivotally supporting the shanks, a bolt passing through the cross-head and the shanks, said bolt having its ends countersunk in the shanks and being fastened 45 against rotation, and a coil spring in the reamer body exerting an upward tension on the mandrel.

13. In an underreamer, the combination 50 of a pair of swinging bits, shanks extending upwardly from the bits, ribs on each side of the bits, a reamer body having an integral tongue depending from its lower end provided with a vertical slot, a mandrel bore in the body above the slot and connected therewith, the body having grooves 55 on each side of the tongue at each side of the slot for receiving the ribs of the shanks and also having radial recesses extending from the grooves for receiving the shanks, 60 a mandrel in the bore of the body having a cross-head in the slot of the tongue, said cross-head being pivotally connected with the shanks, and a coiled spring supported in the bore of the body and surrounding 65 the mandrel and supporting the same, the

body having a transverse opening for admitting a tool for depressing the mandrel.

14. In an underreamer, the combination 70 with a reamer body having a tongue depending from its lower end and tapered sockets on each side of the tongue, said tongue having its lower end rounded, and a spring impelled mandrel within the body, of a pair of bits each having a cutter at its lower end and comprising a bit body and 75 a shank, each bit body having a vertical channel on its inner side for receiving a vertical edge of the tongue, the shanks slidably engaging in sockets of the reamer body and pivotally supported by the mandrel, 80 each shank being cut off at one upper corner and notched on the opposite side to permit the shank and bit body to swing when the bits are lowered, said bit bodies each having a shoulder engaging under the rounded 85 end of the tongue when the bits are collapsed.

15. A bit for an underreamer including, 90 a laterally extending wing, an upright shank above the wing, a boss at the intersection of the wing and shank, and a web connecting the inner side of the wing with the bottom of the shank, the wing having a vertical channel in its inner side, the boss having a sump extending upwardly, in combination with a reamer body receiving and 95 pivotally supporting the shank and having a tongue engaging the channel and a spline engaging in the sump.

16. In an underreamer, the combination 100 of a reamer body, a central tapered tongue extending downwardly from the lower end of the body and provided with a vertical slot, the reamer body having a main bore connected with the slot and also provided 105 with dove-tail sockets extending vertically on each side of the slot, said body being shouldered above its lower end and exposing the side of the tongue, a spline on the side of the tongue extending downwardly 110 from the shoulder, a mandrel extending from the main bore of the reamer body to the slot of the tongue, a cross-head on the lower end of the mandrel within the slot, a pair of bits having dove-tail shanks extending 115 upwardly into the sockets and pivoted on the cross-head, said bits having channels receiving the tongue, the lower end of the tongue being rounded, the bits being collapsible under the rounded end of the 120 tongue, said bits having sumps receiving the splines when the bits are expanded, and a bit expanding spring encircling the mandrel within the main bore of the reamer body.

17. In an underreamer, a reamer body, a 125 central longitudinal tongue extending from one end of the body, said body having sockets in its sides, which sockets taper both radially and longitudinally, bits located at opposite sides of the tongue and having 130

- shoulders adapted to be positioned under the lower end of the body when the bits are in expanded position, correspondingly tapering shanks extending from the bits and 5 slidable in the sockets, a pivotal support for the shanks, and means for moving the pivotal support longitudinally of the reamer body, whereby the bits are moved around the edges of the tongue and expanded.
- 10 18. In an underreamer, a reamer body, a central longitudinal tongue extending from one end of the body, said body having sockets in its sides which sockets taper both radially and longitudinally, bits 15 located at opposite sides of the tongue and having shoulders adapted to be positioned under the lower end of the body when the bits are in expanded position, correspondingly tapering shanks extending 20 from the bits and slidable in the sockets, a pivotal support for the shanks, and means for moving the pivotal support longitudinally of the reamer body, whereby the bits are moved around the edges of the tongue 25 and expanded, said bits, said tongue and said body having tapering contacting surfaces.
19. A bit for an underreamer including, a laterally extending wing, an upright shank 30 above the wing, a boss at the intersection of the wing and shank, and a web connecting the inner side of the wing with the bottom of the shank, in combination with a reamer body receiving and pivotally supporting the 35 shank and having a relatively fixed expanding element disposed at a right angle to said wing and engaged by the inner side of the bit.
20. A bit for an underreamer, including 40 an upright shank, a wing at the lower end of the shank extending laterally beyond one side only of the shank, whereby the shank is offset laterally from the center of the wing, in combination with a body receiving and 45 pivotally supporting the shank and having a relatively fixed expanding element disposed at a right angle to said wing and engaged by the inner portion of the bit.
21. In an underreamer, a body provided 50 with a longitudinally extending tongue and longitudinally extending sockets, longitudinal shanks slidably mounted in the sockets and upon opposite sides of the tongue and 55 adapted to swing in planes substantially parallel with the sides of the tongue, bits carried by the shanks and arranged at substantially a right angle thereto, each bit extending laterally beyond one side only of the shank whereby the shank is offset laterally from the center of the bit, said bits engaging the tongue and being expanded thereby when the shanks are moved longitudinally in one direction, and means to move the shanks longitudinally in one direction. 60
22. In an underreamer, a body provided 65 with a longitudinally extending tongue having opposite sides and longitudinally extending sockets disposed adjacent said opposite sides, longitudinal shanks adapted to move longitudinally within the longitudinal 70 sockets and to turn in planes substantially parallel with said opposite sides of the tongue, bits carried by the shanks and adapted to engage with the edges of the tongue and be expanded thereby, said bits 75 swinging away from the edges of the tongue, and means to effect the longitudinal movement of the shanks.
23. In an underreamer, a body having a longitudinal tongue provided with a longitudinal opening, said body having longitudinal sockets, shanks slidable within the sockets, each shank being provided upon its inner face with a cylindrical recess, a mandrel within the body and having a cross-head disposed within the longitudinal opening of the tongue with the ends of the cross-head projecting laterally beyond the tongue and pivotally seated within the cylindrical 80 recesses, bits carried by the shanks and engaging said tongue, and means to move the shanks longitudinally. 85
24. In an underreamer, a body having a tongue and longitudinal sockets, the end of the body adjacent each longitudinal socket 90 being arranged one above the other in stepped relation, shanks mounted within the sockets, bits carried by the shanks, each bit having its upper end adapted to engage beneath the lower end of the body, a 100 boss carried by the upper end of the bit and projecting above the same to engage beneath the upper end of the body whereby the points of engagement between the bit and its boss with the said lower and upper 105 ends are arranged to break joint, the bits being expanded by engagement with said tongue, and means to move the shanks longitudinally.
- In testimony whereof I affix my signature. 110
- GUSTAVUS A. MONTGOMERY.
